UNITED STATES PATENT OFFICE.

CHARLES WATZ, OF NEW YORK, N. Y.

VEGETABLE-CUTTER.

SPECIFICATION forming part of Letters Patent No. 694,592, dated March 4, 1902.

Application filed April 5, 1901. Serial No. 54,443. (No model.)

To all whom it may concern:

Be it known that I, CHARLES WATZ, a citizen of the United States, residing in New York, borough of Bronx, in the State of New York, have 5 invented certain new and useful Improvements in Vegetable-Cutters, of which the following is a specification.

This invention relates to an improved vegetable-cutter of that class in which a knife-disk 10 provided with a number of radial knives is rotated in front of a suitable feed device in such manner that slices of varying thickness can be cut off, the cutter being also adapted for cutting other articles, as noodles and the like, in a quick and convenient manner; and the invention consists in the combination, in 15 a vegetable-cutter, of a cutter-disk provided with radial openings, center disks provided with hemispherical and radial semicylindrical 20 depressions, said center disks being placed on opposite sides of the cutter-disk, a shaft passing through said disks, means for clamping the disks together thereon, cutting-knives provided with spherical terminals and short 25 cylindrical shanks at their inner ends engaging said depressions, and means for supporting the outer ends of the knives on the cutter-disk; and the invention consists, further, in the combination, with a vegetable-cutter of the 30 construction stated, of means for adjusting said knives to any desired angle relatively to the cutter-disk, as will be fully described hereinafter and finally pointed out in the claims.

35 In the accompanying drawings, Figure 1 represents a side elevation of my improved vegetable-cutter. Fig. 2 is a plan view of the same. Fig. 3 is a front view of the cutter. Fig. 4 is a detail vertical transverse section 40 through the upper part of the standard and feed-table thereon. Fig. 5 is a horizontal section through the cutter-disk; and Figs. 6, 7, and 8 are details showing the adjustment of the knives in said disk, so as to set them for 45 cutting slices of the desired thickness.

Similar letters of reference indicate corresponding parts.

Referring to the drawings, A represents a supporting-standard, which is preferably 50 curved at its upper part and provided at its lower part with a clamping-screw *a*, so as to be attached to a table T or other suitable point

of support. The upper end of the standard A is provided with an eye for inserting the shaft *d* of the knife-disk D and with a concaved extension-arm A', that serves for supporting a feed-table B, preferably made of wood and attached to the extension A' by means of a clamping-screw *a'*, as shown clearly in Fig. 4. The feed-table B is of sufficient 60 length to receive vegetables of ordinary size—such as cucumbers, beets, black radishes, &c.—and permit the slicing of the same by feeding them forward by hand towards the cutting-disk D. 65

The extension A' is provided at its outer end with eyes in which is supported a pintle *a* 2, on which is pivoted a feed-block C, preferably made of wood and which is capable of being swung readily over the pintle into open 70 position, as shown in Fig. 1, or in position so that the lower convex part of the same fits into the concaved feed-table B. At its rear part the feed-block is provided with a suitable handle *c*, by which it can be taken hold of. 75 This block is used only when the vegetables or other articles to be cut become so small that they can no longer be handled by the hand without danger to the fingers, in which case the feed-block is swung over onto the 80 feed-table and slid forward on the same and upon its pintle, so that the article to be cut is fed forward without danger to the fingers.

The cutter-disk is preferably provided with 85 four radial openings and four radial and correspondingly-located knives, as shown in Fig. 3. The knives D² are set into the openings and adjusted at a suitable inclination to the plane of the disk D, according to the size of slices to be cut. The shaft *d* of the 90 disk is provided with a circumferential recess *d'*, so as to be locked in position into the eye of the standard by a key *b*, engaging said annular recess *d'*, but prevented from turning freely on its axis in the eye. When it is desired to exchange the cutter-disk for a grating or other disk, the key *b* is withdrawn and the shaft of the grater or other disk inserted and locked by replacing the key, so that the 95 cutter can then be used for grating or other 100 purposes.

The cutter-disk D is supported by two disk-shaped center plates *b'* *b*², which are placed upon the shaft and which are provided with

hemispherical depressions that register with the equidistant knife-openings in the disk. The disks b' b^2 are held between a shoulder of the shaft d and a washer b^3 , placed on the 5 face-disk between the same and the hub h of the handle H , said hub being provided with an interiorly-threaded socket that is screwed over the front end of the shaft d , as shown clearly in Fig. 5. When the parts are thus connected, 10 the center disks serve to support the inner ends of the cutting-knives D^2 , which are provided with short cylindrical shanks c' and spherical terminals c^2 , said shanks and terminals being supported in the hemispherical 15 and semicylindrical depressions, as shown in Fig. 5. The outer end of each cutting-knife is turned over so as to form a web e and provided with two pins e' e^2 , the pin e' being located on the cranked portion or web e , near 20 the blade of the knife, while the pin e^2 is located at the outer end of the web, as shown in Fig. 6. The cutter-disk is provided with a circumferential flange b^4 , that extends over the cranked web e of the cutting-knives and 25 is provided with openings for the pins e' , which are passed through and pivoted in the same. The back of each cutting-knife is bent over so as to form a flange d^2 , grooved, as shown in Fig. 8, whereby the back of the knife engages and is reliably supported by the cutter-disk. The flanged cutter-disk D is surrounded by a metallic ring E , which is provided 30 with openings for engaging the end pin e^2 of each cutting-knife, said ring being also further provided with slots e^3 , registering with screw-threaded openings in the cranked web of the cutting-knives for inserting clamping-screws f , that form connection between the web of the knives and the cutter-disk and the 35 adjusting-ring E . When it is desired to adjust the blades of the knives to greater or less inclination to the plane of the cutter-disk, the screws are loosened and the ring E shifted in one or the opposite direction, so as to move the 40 knives on their axes by the connection of the ring E with the pin e^2 until the blades of the knives are set to the proper inclination. When this is accomplished, the clamping-screws are tightened, so that the knives are 45 rigidly held in position. In this manner all the knives can be simultaneously adjusted and firmly secured after adjustment, so as to be set at a greater or less angle of inclination to the plane of the cutter-disk, and produce 50 thereby the cutting of thicker or thinner slices, as required.

The cutting-knives are preferably provided with a convex cutting edge, but with straight backs, the openings in the cutter-disk being 55 of corresponding shape, but of size slightly larger than the knife, so as to permit the free egress of the slices through the openings into a suitable receptacle placed below the cutter-disk. The turning of the knives when being 60 adjusted by the shifting of the outer ring is readily accomplished, it being permitted by the spherical bearings of the center disks,

which offer no resistance to the adjustment. The outer end of the shaft d is preferably made hexagonal, as shown in Fig. 5, so as to 70 be tightly applied to the hub h by means of a suitable wrench or key.

When the vegetable-cutter is desired to be used for cutting larger vegetables, noodles, and other articles, &c., an extension feed-table B^2 is used, which is hinged to the rear end of the main feed-table B and which carries at its outer end a wire stay or brace g , that is hinged to the under side of the same. The upper side of the table B^2 is made of the 80 same concavity as the main feed-table. When this extension feed-table is required, it is swung up into line with the main feed-table and supported on the brace g , which is bent over at the lower end, so as to form supporting-feet. When not required for use, the brace is folded up on the under side of the feed-table and the latter dropped into position below the main feed-table. The extension feed-table forms a very useful attachment to the vegetable-cutter, which is of 85 great advantage in families and households in which noodles, macaroni, and similar articles are consumed.

The advantages of my improved vegetable-cutter are that the cutter-disk can be readily removed from the supporting-standard and the individual knives conveniently removed for resharpening whenever required. The knives and parts can then be readily assembled again by replacing the clamping-screws between the outer adjusting-ring and the webs of the knives and screwing up the center disks upon the inner ends of the cutting-knives by the screw-hub of the handle. 100 Another advantage is the facility of cleaning the cutter-disk and the convenience in feeding articles to be cut by means of the feed-block when the hand-feeding of the same 105 cannot be done with safety. A further advantage is that the cutter-disk can be replaced by a grater or other disk, so as to accomplish other operations besides slicing. Finally, the feed-block extension has the 110 advantage of permitting the cutting up of large 115 articles, as mentioned.

Having thus described my invention, I claim as new and desire to secure by Letters Patent—

1. In a vegetable-cutter, a cutter-disk provided with radial openings, center disks provided with hemispherical and radial semi-cylindrical depressions, said center disks being placed on opposite sides of the cutter-disk, a shaft passing through said disks, 120 means for clamping the disks together thereon, cutting-knives provided with spherical terminals and short cylindrical shanks at their inner ends engaging said depressions, and means for supporting the outer ends of 125 the knives on the cutter-disks, substantially as set forth.

2. In a vegetable-cutter, a cutter-disk provided with radial openings and a circumferen-

- 5 tial flange, center disks provided with hemispherical and radial semicylindrical depressions, said center disks being placed on opposite sides of the cutter-disk, a shaft passing through said disks, means for clamping the disks together thereon, cutting-knives provided at their inner ends with spherical terminals and short cylindrical shanks engaging said depressions, and at their outer 10 ends with pins pivoted in the circumferential flange of the cutter-disk, and means engaging said knives at their outer ends for adjusting the same relatively to the cutter-disk, substantially as set forth.
- 15 3. In a vegetable-cutter, a cutter-disk provided with radial openings and a circumferential flange, cutting-knives in said openings, having grooved backs engaging said disk,

spherical terminals and short cylindrical shanks at the inner ends of said cutting-knives, center disks provided with depressions for supporting said terminals, a cranked web at the outer end of each knife, pins on said web, one pin engaging the flange of the disk, an adjusting-ring engaging the other pin of 25 each web, and clamping-screws connecting said adjusting-ring with said cranked webs, substantially as set forth.

In testimony that I claim the foregoing as my invention I have signed my name in presence of two subscribing witnesses.

CHARLES WATZ.
